UNITED STATES PATENT OFFICE.

ALBERT P. BONNAFFONS, OF NEW ORLEANS, LOUISIANA.

STATION-INDICATOR AND ADVERTISER.

No. 869,154.

Specification of Letters Patent.

Patented Oct. 22, 1907.

Application filed September 29, 1906. Serial No. 336,741.

To all whom it may concern:

Be it known that I, ALBERT P. BONNAFFONS, a citizen of the United States, and a resident of New Orleans, in the parish of Orleans and State of Louisiana, have **5** invented a new and Improved Station-Indicator and Advertiser, of which the following is a full, clear, and exact description.

This invention relates to an improved device for automatically indicating the successive stations or streets **10** along a railway, tramway or other line of passenger transportation.

The invention is intended particularly for use in street railway service, but is useful in other connections.

15 The object of the invention is to provide an indicator which will be automatically operated as the car passes along the track, and exhibit to the view of the passengers the name of the next station or street crossing.

A further object of the invention is to provide means **20** whereby the passengers may be notified as to the next street, irrespective of the direction in which the car is moving, so that no manipulation of the indicator is necessary at the end of the trip, the parts being so constructed that the indicator used when the car is going **25** in one direction is held stationary upon the return trip, and a second indicator at the opposite end of the car serves to indicate the stations in their proper order upon the return trip.

Another object of the invention is to provide means **30** whereby the car may, if necessary, back up for a few squares at any point along the route without interfering with the normal operation of the indicator and without causing any disarrangement thereof.

A further object of the invention is to provide means **35** for operating the indicator, which means is entirely independent of the car wheels, and is so supported that it is kept upon the track irrespective of the curvature or changes in elevation thereof. As this operating means is entirely independent of the car wheels, it is **40** not affected by the slipping or sliding of the cars along the track due to the condition of the latter or to the application of the brakes.

Further objects of the invention will be hereinafter pointed out, and the structure by which said objects are **45** attained clearly defined in the claims.

Reference is to be had to the accompanying drawings forming a part of this specification, in which similar characters of reference indicate corresponding parts in all the figures, in which

50 Figure 1 is a side elevation of a street car provided with my improved station indicating means, a portion of the car being broken away to more clearly show the latter; Fig. 2 is a vertical cross section of the car shown in Fig. 1; Fig. 3 is a plan view of the auxiliary axle, **55** wheels and supporting means, which serve to operate the indicator; Fig. 4 is a vertical cross section through

the indicator; Fig. 5 is a detail section showing a portion of the means employed to accommodate the device to unevenness or curvature of the track, said section being on the line 5—5 of Fig. 11; Fig. 6 is a detail showing the ratchet connections between the vertical drive shaft and the horizontal drive shaft of each indicator; Fig. 7 is an inverted plan view of the parts shown in Fig. 6, a part appearing in section on the line 7—7 in said figure; Fig. 8 is a detail section on the line 8—8 of **60** Fig. 2; Fig. 9 is a detail showing the means whereby the direction of the car may be reversed for a short distance without interfering with the normal operation of the indicator; Fig. 10 is a section on the line 10—10 of Fig. 9; Fig. 11 is a section on the line 11—11 of Fig. 5; **65** 70 and Fig. 12 is a vertical section on the line 12—12 of Fig. 3.

My invention is particularly adapted for use upon street cars which travel back and forth over the line without said cars being turned around at the end of the **75** line. As one end of the car is the front when the car is going over the route in one direction and the opposite end of the car is ahead when the car is going over the route in the opposite direction, I provide two indicators, one at each end of the car, and means whereby **80** only the indicator which is at the front end of the car will be operated, the indicator at the rear end of the car being held stationary and exhibiting an advertisement, for instance, throughout the length of the return trip.

Preferably, the indicator comprises a drum 1 having a plurality of sheets or flexible flaps 2 secured thereto at intervals entirely around the circumference of the drum, and each of the sheets or flaps is provided with a weight 3 at its free end, whereby when said end is **85** liberated it may drop down and hang in a vertical plane from the surface of the drum to indicate the approaching street and also display an advertisement if desired.

As the stopping places of the car are at varying distances apart and as it is desirable to have each indicating flap drop at the proper time, I provide each flap or as many of them as may be required with small tags **90** 3^a the lengths of which are so adjusted for each individual flap that it falls at the proper time irrespective of the distance between stations or street crossings.

The drum is preferably supported in a protecting casing having end plates 4 serving as bearings for the shaft 5 of the drum, and having a cover or longitudinal portion 6 extending over the upper part of the drum. The cover is provided with a removable section 7 carrying a spring 7^a for engagement with the tags 3^a of the flaps so as to control the dropping thereof and also carrying sector-shaped portions 8 fitting into and constituting portions of the ends of the casing. The removable section 7 is held in place by strips 9, secured **95** to the ends of the casing and having openings adapted to receive short pins on the removable section, and

additional strips 10 and 11 are provided at the ends, one of said strips being secured to the removable section and the other strip secured to the stationary portion. The strips 10 and 11 are adapted to lie side by side and within the casing, so as to prevent longitudinal, as well as vertical, displacement of the removable section. The casing of the drum is provided with a base-plate 12 of any suitable character, by which the entire device may be supported upon the end wall of the car.

The shaft 5 of the drum extends out through the casing at one end, and is provided with a large gear wheel 13, meshing with a smaller gear-wheel 14 on a shaft 15, journalized in suitable journal boxes on the end of the car and supported substantially parallel to the shaft 5 of the drum. The end of this shaft 15 carries a bevel gear 16, meshing with a bevel gear 17 on the end of a vertical shaft 18, which latter extends to a point adjacent the floor of the car and preferably beneath the seats thereof, whereby the operating mechanism thereof will be protected. A longitudinal shaft 19 is provided beneath one seat of the car and extends substantially the entire length of the body of said car. Each end of the shaft 19 is provided with a bevel gear 20, meshing with a bevel gear 21 on the lower end of each of the vertical shafts 18, and means are provided for rotating the shaft 19 when the car is in motion, the direction of rotation of said shaft reversing as the direction of the car reverses.

For causing the rotation of one of the indicators when the car is going in one direction, and for positively preventing the rotation of the other indicator, I provide the following means, shown in Fig. 2, but more clearly disclosed in Figs. 7 and 8. The gear wheel 17 at the upper end of each of the shafts 18 is loosely mounted thereon and is supported upon a small ratchet wheel 22, carried by and rigidly secured to the shaft 18. The under side of the gear wheel 17 is provided with a spring-pressed pawl 23, adapted to engage with the ratchet wheel 22 and cause the rotation of the gear wheel 17 when the shaft is rotated in one direction, but permitting the gear wheel 17 to remain stationary when the shaft 18 rotates in the opposite direction. The ratchet wheels 22 and pawls 23 beneath the two gears 17 are so constructed that motion is imparted to one of the gears 17 when the shaft 19 is rotated in one direction; and motion is imparted to the other gear wheel 17 when the shaft 19 rotates in the opposite direction. In order to positively prevent the gear wheel 17 from being carried along with the ratchet wheel 22 and shaft 18 when the latter rotates in a direction which would normally cause the teeth of the ratchet wheel to freely slip beneath the pawl 23, I provide means for holding the shaft 15 from rotating in that direction. This means consists in a ratchet wheel 24, rigidly secured to the shaft 15, adjacent a loose collar 25 on said shaft. The collar is provided with a weighted lever 25^a suspended therefrom and serving to normally prevent the rotation of the collar. This collar is provided with a spring-pressed pawl 26 in engagement with said ratchet wheel, and the teeth of the ratchet wheel normally pass beneath the pawl when the shaft is rotated to operate the station indicator in the proper direction; but the pawl engages with the teeth and prevents the rotation of the shaft 15 and of the station indicator in the

opposite direction. This weighted lever 25^a may, if desired, be secured to the end of the car as a bracket or may be employed as a handle to regulate the indicator by hand after the car has been on a side-track, to the barn or indicates incorrectly from any other cause.

Within the car at a point intermediate its ends and in some protected position, as, for instance, beneath one of the seats, is located a gear wheel 27 on the longitudinal shaft 19, and this meshes with a gear wheel 28 on a short shaft, serving to communicate motion to the said shaft 19. The opposite end of this short shaft carries a bevel gear 29 meshing with a bevel gear 30 on a shaft 31, parallel to the main longitudinal shaft 19, and this second shaft 31 carries a worm gear 32 extending into a vertically-disposed mounting 33, and meshing with a worm 34 located therein. The worm is mounted on a short shaft 35, and is free to slide longitudinally thereof, but is prevented from rotating thereon by means of a key 36. The mounting 33 for the vertical shaft 35 holds the worm 34 from longitudinal movement and in engagement with the worm gear 32, but permits the free longitudinal motion of the shaft 35. This latter shaft extends through the floor of the car and is connected by two universal joints 37 and 38 and an intermediate section 39 to a short shaft 40, having a bevel gear 41 adapted to mesh with a bevel gear 42 upon the auxiliary axle 43. This axle is mounted in bearings 44 and 45 on a frame 46, which latter is secured by a pivot pin 47 to a bracket 48, carried by a stationary portion 49 of the car-truck. As the frame 46 is secured to the car-truck at but one point and is pivoted at that point, it is evident that the frame may freely swing from side to side and independent of the car-truck, whereby the two small wheels 50 and 51 may be maintained upon the track at all times. The pivot pin 47 does not bind the supporting frame 46 to the bracket 48, but permits the outer end of the frame to be raised and lowered through a reasonable distance, so that the frame and the small wheels 50 and 51 may raise and lower and accommodate themselves to unevenness in the track.

As the auxiliary axle 43 and its supporting frame is moved to one side or raised or lowered, due to curvature or unevenness of the track, it is evident that the short shaft 40 is raised and lowered or otherwise moved simultaneously; but as the shaft 40 is connected to the shaft 35 by means of two universal joints, it is evident that there is nothing to interfere with the free movement of the frame and auxiliary axle, and that motion will be imparted to the mechanism within the car as the auxiliary axle 43 is rotated. Only one of the small wheels 50 and 51 is secured to the auxiliary axle, while the other small wheel is loosely mounted thereon, whereby it may round curves without causing any slipping of either of the wheels.

The small wheels carried on the auxiliary axle 43 merely travel over the track and meet with very little resistance, as the indicating mechanism within the car requires but little power to operate it. These small wheels are unaffected by the brakes of the car or by the slipping of the car wheels due to the condition of the track. In other station indicating means in which the indicator is operated from the main car axle, it is evident that should the car encounter a slippery portion on the track, the car wheels would continue to ro-

tate without forcing the car ahead at the required speed, and as the indicator would be operated by the car axle it would soon become entirely disarranged and indicate stations a long time before the car approached such stations, and often when the brakes are applied to the car wheels, the wheels are held from rotating and merely slip along the track. This would prevent the indicator from operating, even though the car were still moving and the indicator, therefore, would not indicate the 10 stations until after they were passed. In my improved indicator and operating mechanism therefor, above described, it is evident that as the small wheels are entirely independent of the brakes or of the traction motor, they serve as a true indicator of the progress of 15 the car and properly indicate the signals.

As the auxiliary axle 43 extends entirely across the track, and is provided with two small wheels and the frame for supporting said axle is free to move a sufficient distance for these small wheels to be kept upon the 20 track at all times, it is evident that there is no possibility of the small wheels getting off the track, as would be the case were there only one wheel and that supported in alinement with one of the main car wheels. In the latter case, the small wheels would almost inev- 25 itably jump the track as the car rounded a sharp curve.

In order to permit of the backing of a car for a short distance along the route without in any way interfering with the signal, or causing the operation of the signal at what was the rear end of the car, I provide a special 30 form of clutch, shown in Figs. 1, 9 and 10. The gear wheels 20 upon the opposite ends of the shaft 19 are loosely mounted thereon and are held in place by collars 52. One side of each bevel gear 20 is provided with a single tooth 53, adapted to engage with the single 35 tooth 54 on a collar 55, secured to the shaft 19 in any suitable manner. As the shaft 19 is rotated the tooth 54 of the collar 55 engages with the tooth 53 of the bevel gear wheel 20 and causes the rotation of the latter, but should the car reverse its direction a short distance 40 at a point intermediate its route, the tooth 54 would be moved away from the tooth 53 of the bevel gear and no reverse motion of the indicator would be effected. The indicator would remain stationary while the car was backed up to permit the passage of a team, to hook onto 45 a car behind, or for any other reason, and when the car started ahead again the indicator would remain stationary until the car reached the exact point at which it had begun to reverse, and then the indicator would again operate in exactly the same manner as though 50 the car had not been reversed. The advantage of this construction is very readily apparent, as were no such means provided, it is evident that a portion of the route in being traversed the second time would cause the operation of the indicator and cause it to indicate sta- 55 tions in advance of their arrival.

Having thus described my invention, I claim as new and desire to secure by Letters Patent:

1. A station indicator, comprising a drum, a plurality of indicating flaps of flexible material secured thereto, a weight at the end of each of said flaps, tags carried by certain of said flaps intermediate the side edges and extending beyond the free end thereof, resilient means adapted to engage with said tags and release the flaps in succession as the drum is rotated, and means for rotating said drum in one direction.

2. A station indicator, comprising a drum, a plurality

of weighted flexible flaps secured thereto around the circumference thereof, tags secured to certain of the flaps adjacent the free edges and intermediate the width of said flaps, a casing surrounding said drum and flaps, said casing 70 having a removable section, resilient means carried by said removable section for engaging with the tags and releasing the flaps in succession as the drum is rotated, and means for rotating said drum in one direction.

3. A station indicator, comprising a drum, a plurality of 75 indicating flaps secured thereto and adapted to drop to a vertical position when released, and means for rotating said drum to release said flaps in succession, said means including two shafts, gears for conveying motion from one shaft to the other, one of said gears being loosely mounted upon its shaft, a ratchet wheel carried by said shaft, means carried by said loosely mounted gear for engaging with said ratchet wheel and causing the rotation of the gear wheel when the shaft is rotated in one direction, a ratchet wheel mounted on the second shaft, and means adapted to engage with said last mentioned ratchet 80 for normally preventing its rotation in one direction.

4. In combination with a car, an indicator located therein, and means adapted to engage with the car rail to operate the indicator as the car is moved, said means including a lost motion device comprising a shaft, a gear wheel loosely mounted thereon, a collar carried by the shaft and having a tooth, and a second collar carried by the gear wheel and having a tooth, said teeth adapted to 85 contact to cause the simultaneous rotation of the gear wheel and the shaft.

5. In combination with a car, an indicator located at each end thereof, and means whereby the indicator at one end of the car will be operated when the car is going in one direction, and said indicator held stationary and the 100 indicator in the opposite end of the car operated when the car is going in the reverse direction, said means including a shaft, a ratchet wheel, a collar loosely mounted on the shaft, a pawl mounted on the collar and in engagement with the ratchet wheel, and a weighted lever suspended 105 from the collar.

6. In combination with a car, two indicators located therein, and means whereby one indicator will be held stationary and the other indicator operated when the car is going in one direction, and whereby the first mentioned indicator will be operated and the second mentioned indicator held stationary when the car is going in the reverse direction.

7. In combination with a car, two indicators located therein, means adapted to engage with the car rail for operating both of said indicators, means whereby one of the indicators will be held stationary and the other indicator operated when the car is going in one direction and whereby the first mentioned indicator will be operated and the second mentioned indicator held stationary when the car is going in the reverse direction, and means whereby the direction of the car may be reversed a short distance without effecting the operation of either indicator.

8. In combination with a car, an indicator located therein, and means adapted to engage with the car rail to operate said indicator, said means including an auxiliary axle, two car wheels mounted thereon and adapted to travel on the two rails, and a pivoted frame adapted to support said axle whereby it may follow the car track irrespective of the curvature or unevenness of the latter.

9. In combination with a car, a station indicator located therein, and means adapted to engage with the car track and operate said indicator, said means including a pivoted frame, an auxiliary axle supported therein, wheels mounted on said axle and adapted to engage with the car rails, a gear wheel carried by said axle, a substantially vertical shaft having a universal joint therein and a gear wheel adapted to engage with the first mentioned gear wheel, means for slidably mounting a portion of the said shaft, and a gear wheel slidably mounted on said shaft 115 but held from rotation in respect thereto.

In testimony whereof I have signed my name to this specification in the presence of two subscribing witnesses.

ALBERT P. BONNAFFONS.
